UNITED STATES PATENT OFFICE

WILLIAM E. WINE, OF TOLEDO, OHIO

RAILWAY CAR

Application filed August 28, 1929. Serial No. 389,016.

My invention relates to railway cars and more particularly to improvements in the lading discharge doors thereof.

One of the principal objects of the invention is to provide strong and simple means for stiffening and reinforcing such doors.

Another object of the invention is to so form the door stiffeners and to associate them with the doors that the car frame members and appurtenances on the side of the car will not interfere with mechanism employed for co-operating with the stiffeners to support the door in closed position.

A primary feature of the invention resides in providing the door with a plurality of stiffening members provided with door contacting flanges which converge from adjacent the hinged edge of the door to adjacent the opposite edge thereof.

Another feature of the invention consists in forming the stiffening members with portions disposed substantially normal to the door which converge toward each other from a point intermediate the edges of the door to adjacent the edge thereof remote from the hinge axis.

Other and more specific features of the invention residing in advantageous forms, combinations and relations of parts will hereinafter appear and be pointed out in the claims.

In the drawings illustrating a preferred embodiment of the invention:

Figure 1 is a fragmentary plan view, partly in section, of a gondola car showing the invention associated therewith.

Figure 2 is a fragmentary side elevational view of the construction illustrated in Figure 1.

Figure 3 is a sectional view taken on line 3—3, Figure 1.

Figure 4 is a plan view of the door stiffener.

Figure 5 is an end view of the stiffener.

Figure 6 is a sectional view taken on line 6—6, Figure 4.

Figure 7 is a sectional view taken on line 7—7, Figure 4.

For purposes of illustrating the invention a gondola car having pressed steel doors has been illustrated, but it will be appreciated that the invention is not limited in its appli-

cation to cars and doors of this type. Furthermore, since the construction of the stiffeners applied to each door of the car is the same, only one door and the portion of the car construction immediately adjoining it has been illustrated.

Referring more particularly to the drawings, 1 indicates one of the center sills and 2 one of the side sills thereof, the latter being preferably of channel shape, having upper and lower substantially horizontal flanges 3 and 4, respectively, and an intermediate connecting web 5. The wooden sides 6 of the car are, as is usual, strengthened and reinforced by side stakes 7 and diagonally extending braces 8. The floor of the car is preferably formed by a plurality of transversely extending wooden boards or planks 9 which are supported by the cross bearers 10 of the car connected to the lower ends of the side stakes. The floor also comprises longitudinally extending boards or planks 11 which extend between the respective planks 9 and overlie the center sill. It will thus be perceived that these transversely and longitudinally extending planks, together with the inwardly projecting flanges 4 of the side sills, define a plurality of openings through which lading within the car may be discharged.

These openings are respectively closed by hingedly mounted doors 12, only one of which is illustrated in the drawings. These doors are preferably made of sheet metal having downwardly projecting marginal flanges 13 and transversely extending stiffening corrugations 14. The side marginal flanges of the door are preferably inclined downwardly to co-operate with corresponding inclines with which the adjoining edges of the transverse planks are provided. To prevent the escape of fine lading between the hinged edge of the door and adjoining portions of the longitudinally extending planks 11, plate-like members 15 are secured to the latter and project into the opening to overlie the adjacent portion of the door. To prevent the escape of fine lading between the outer edge of the door and the adjacent portion of the side sill the inwardly projecting flange 4 thereof overlaps

the upper surface of the portion of the door immediately adjacent its outer edge.

Secured to the under face of the door are a plurality of stiffening members 16 which extend from a point adjacent the hinged edge of the door to a point beyond the opposite edge thereof. In order that the outer ends of the stiffening members may pass beneath the adjacent marginal flange of the door, 10 each is preferably offset intermediate its ends as at 17. Each of the door stiffeners is provided with a top door contacting flange 18, a depending portion or web 19 disposed in a plane substantially normal to that of the door 15 and a lower flange 20 spaced from and substantially parallel to the top flange 18. At its inner end the door contacting flange of each stiffener is formed with extensions 21 which are apertured to receive rivets 22 for 20 attaching the stiffener at this point to the door. The top flange is also provided with other apertures 23 for receiving additional rivets 24 to further attach the stiffener to the door. At its inner end the stiffener is also 25 preferably provided with an end wall 25 substantially normal to the door and parallel with its hinge axis. This rear wall 25 is provided, preferably integrally, with a lug 26 having an aperture for receiving a pin 27 to 30 hingedly connect the door to a bracket 28 rigidly secured to adjoining portions of the center sill 1.

The flanges 18 of the projecting ends of the stiffeners 16 are respectively adapted to 25 co-operate with mechanisms 29 secured to the side sill for supporting the door in closed position. These mechanisms each comprise a pivoted hook 30 having a shoulder adapted to engage the under side of the flange 18.

It is desirable to secure the inner ends of the stiffeners to the door at points adjacent its side edges so that at its hinged edge the door will be supported at points spaced a relatively great distance apart. However, it 45 is necessary to bring the outer projecting ends of the stiffeners closer together so that the diagonal braces 8 and appurtenances, such as ladders 32, will not interfere with the mounting and free operation of the mechanisms 29 employed for co-operating with the stiffeners to support the door in closed position. Furthermore, it will be appreciated that it is desirable to mount the door supporting mechanisms relatively close together, 50 as then a practically three point support is provided for the door. The advantages of supporting any member, such as a door, at three points are, of course, well known.

In order to arrange the stiffeners for each door so that their outer ends will be closer together than their inner ends, the top flanges 18 of the stiffeners converge from adjacent the hinged edge of the door to adjacent the opposite edge thereof. While the depending 60 portions or webs 19 and the lower flanges 20

thereof also converge toward each other, they do not converge from adjacent the hinged edge of the door, but start to do so at points intermediate the edges of the door, preferably substantially midway therebetween. Thus, the portions of the webs 19 adjacent the hinged edge of the door are substantially parallel to each other and normal to the hinge axis of the door, but at points remote from the hinged edge they are respectively disposed in planes forming oblique angles with the hinge axis. Since the web portions start to converge from points spaced outwardly from the points where the top flanges start to converge, the latter project on opposite sides of the web between the hinged edge of the door and the points where the webs start to converge, but only project on one side thereof from the latter points to the outer ends of the stiffeners. It is preferred that the lower flange 20, as it is of less width than the top flange, only project from one side of the web throughout its entire length. 75

Adjacent its outer end each of the door stiffeners may advantageously be integrally formed with an upwardly projecting flange 33 for attachment to the adjacent marginal flange of the door. This flange is somewhat wider than the top flange 18, so that a plurality of rivets 34 may be employed to effect 80 the connection between it and the flange of the door. At one side of the stiffener the flange 33 is preferably connected thereto by a rib or gusset 35 which is disposed substantially in the same plane as the top flange 18, 85 while on the opposite side thereof, namely, the side adjacent the door supporting mechanism, the flange extends downwardly below the top flange 18, merging with the web and lower flange 20. Triangular shaped gussets 90 36 may also be conveniently provided for connecting the flange 33 to the top flange 18. This flange, due to its rigid connection with the marginal flange of the door, adequately 95 serves to resist the torsional moments induced in the stiffener as a result of its engagement with the pivoted hook 30. 100

As it is often difficult to effect complete closure of sheet metal doors of the type illustrated due to their becoming warped or distorted on account of the severe service conditions to which they are subjected, each stiffener is preferably formed with a laterally projecting portion 37 to receive a removable door prying lever (not shown). When the lever is inserted in the portion 37 it engages with the outer marginal flange of the door and projects outwardly therebeyond a sufficient distance to afford the necessary leverage for moving the door to a fully closed position. 115

From the foregoing it will be perceived that while the door stiffener is of simple design, it adequately serves to reinforce the door and to co-operate with means for supporting the latter in closed position. 120

I claim:

1. In a railway car having a lading discharge opening, the combination with a hinged door for closing said opening, of a plurality of stiffening members secured to said door and extending from adjacent the hinged edge thereof to a point beyond the opposite edge, said members respectively having flanges disposed in a plane parallel with the door, said flanges converging toward each other from adjacent the hinged edge of the door to adjacent the opposite edge thereof.

2. In a railway car having a lading discharge opening, the combination with a hinged door for closing said opening, of a plurality of stiffening members secured to the door, each of said members having a door contacting flange and a portion substantially normal thereto, the door contacting flanges of the members converging toward each other from adjacent the hinged edge of the door and the normal portions of the members converging toward each other from points remote from the hinged edge of the door.

3. In a railway car having a lading discharge opening, the combination with a hinged door for closing said opening, of a plurality of stiffening members secured to the door, each of said members being provided with a door contacting flange and a portion substantially normal thereto, said normal portion of each of the members terminating in a marginal flange, the door contacting flanges of the members converging toward each other from adjacent the hinged edge of the door to adjacent the opposite edge thereof.

4. In a railway car having a lading discharge opening, the combination with a hinged door for closing said opening, of a plurality of stiffening members secured to the door, said members having portions disposed substantially normal to the door, the normal portions of the members being substantially parallel from adjacent the hinged edge of the door to points intermediate the edges of the door and converging toward each other from said last named points to the opposite edges of the door, said parallel portions of the stiffeners being respectively provided with door contacting flanges projecting on opposite sides thereof and said converging portions of the stiffeners being respectively provided with door contacting flanges projecting from only one side thereof.

5. In a railway car having a lading discharge opening, the combination with a hinged door for closing said opening, of a plurality of stiffening members rigidly secured to the door, said stiffening members being respectively provided with portions disposed substantially normal to the door, said normal portions converging toward

each other from points intermediate the edges of the door to adjacent the edge of the latter remote from the hinge axis, said normal portions of the stiffener being provided with lower marginal flanges which converge therewith.

6. In a railway car having a lading discharge opening, the combination with a hinged door for closing said opening, of a plurality of stiffening members secured to the door, each of said stiffening members being provided with spaced flanges, one of the flanges of each of said members converging toward each other from adjacent the hinged edge of the door to adjacent the opposite edge thereof and the other of said flanges converging toward each other from points intermediate the edges of the door to adjacent the edge of the latter remote from the hinge axis.

7. In a railway car having a lading discharge opening, the combination with a hinged door for closing said opening, of a plurality of stiffening members rigidly secured to the door, each of said members having spaced flanges connected by a web portion disposed in a plane substantially normal to the door, one of the flanges of each of the door stiffeners converging toward each other from points adjacent the hinged edge of the door to the opposite edge thereof and the other flanges of the members and the webs thereof converging toward each other from points spaced from the points of convergence of said first named flanges.

In testimony whereof I affix my signature.
